UNITED STATES PATENT OFFICE.

ARTHUR F. PYM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Application filed February 3, 1926. Serial No. 85,680.

This invention relates to lasting machines, and more particularly to means for lasting the toes of shoes. The invention is herein illustrated in its application to a bed-lasting machine of the same general type as that shown and described in United States Letters Patent No. 1,018,477, granted on February 27, 1912, upon an application of Matthias Brock, but it is to be understood that the invention is not limited to machines of the particular type illustrated in that patent. In lasting machines that include in their organization means for wiping the upper heightwise of the toe, i. e., for upwiping the upper, the toe wipers during the upwiping operation should follow as closely as possible the heightwise contour of the sides of the toe of the last, so as to apply effective upwiping pressure to the upper. As lasts are positioned in bed-lasting machines, the angular relation of the sides of the toe to the machine usually varies with rights and lefts, and also frequently with different styles of lasts, so that satisfactory results require a similar variation in the direction of the upwiping movement of the wipers. In accordance with my observation the heightwise contour of the sides of the toe in lasts of different shapes bears such a relation to what may be conveniently termed the lateral slope of the bottom of the forepart, that is, the slope represented by straight lines across the toe joining the opposite edges of the last bottom, that this slope may best be used for reference in determining the proper direction of the upwiping movement. The present invention accordingly provides means for determining the direction of the upwipe by the lateral slope of the bottom of the forepart of the last. In its application to machines of the type illustrated, having means for adjustably tipping the toe wipers to conform to the lateral slope of the bottom of the forepart, the invention further provides connected means for thus adjusting the wipers and for simultaneously determining the direction of their upwiping movement, the construction herein shown being such that the direction of the upwipe, in any position of the wipers, is substantially perpendicular to the direction in which the wipers extend laterally of the last. Since it is the practice to adjust the toe wipers in the manner above mentioned, not only for differences between right and

left lasts and between different styles of lasts, but also in accordance with such small variations as there may be in the positioning of different lasts of the same shape in the machine, substantial insurance is thus afforded that the direction of the upwipe will bear substantially the same angular relation to the lateral slope of the bottom of the forepart in different lasts. With the wipers so adjusted that they extend laterally in a direction substantially parallel to the lateral slope of the bottom of the forepart, it follows that the direction of the upwipe will be substantially perpendicular to that slope, a relation which my experience indicates to be the best for the results in view. A further advantage of the construction shown is that the operator of the lasting machine is not required to give attention to any adjustment other than heretofore in the use of such machines.

The invention will now be more particularly described by reference to the accompanying drawings and thereafter pointed out in the claims.

In the drawings,

Fig. 1 is a view in front elevation of the toe-lasting end of a machine of the type shown in the previously mentioned Brock patent;

Fig. 2 is a view on a larger scale in left-hand end elevation of portions of the machine, with parts in section;

Fig. 3 is a perspective view of a portion of the mechanism for determining the path of the upwiping movement of the toe wipers;

Fig. 4 shows in greater detail a portion of the structure shown in Fig. 3; and

Fig. 5 is a view of a shoe and associated parts of the machine, partly in elevation and partly in section on the line V—V of Fig. 1, indicating also by dotted lines a cross-section of the forepart of the last to show more clearly the relation of the sides of the last to the toe wipers.

As more fully shown and described in the prior patent above mentioned, the machine is provided with shoe-positioning means comprising a spindle 10 arranged to enter the spindle hole customarily formed in the heel end of the last, a toe rest 12 upon which the forepart of the shoe is supported, and a heel band 14 for embracing and clamping the heel end of the last and shoe in predetermined relation to the heel wipers (not

herein shown). There is also provided a hold-down 16 for engaging and clamping the forepart of the shoe upon the toe rest 12. The toe-lasting mechanism comprises toe-
5 embracing wipers 18 which are movable upwardly and downwardly by means of a vertically movable support 20 connected by a link 22 to a double-acting treadle 24. The wipers are advanced and closed by means of
10 a hand lever 26. It will be understood that, while holding the wipers closed about the toe by means of the lever 26, the operator raises them by means of the treadle 24 to wipe the upper upwardly over the end and
15 sides of the toe portion of the last to the edge of the insole, and thereafter advances and closes them inwardly over the bottom of the last to wipe the upper over the insole, after which he may increase the downward
20 pressure of the wipers upon the upper by reverse movement of the treadle.

Upon the support 20 there is mounted a slide 28 movable by means of a hand-wheel 30 to adjust the toe wipers 18 lengthwise of
25 the shoe. Upon the slide 28 is a slide 32, controlled as hereinafter explained, for imparting to the toe wipers, in the vertical movement of the support 20, movement relatively to said support in directions laterally of the shoe. Pivotaly mounted at 34 on a plate 35 which is carried by the slide 32 is a holder 36 adjustable by means of a screw 38 and a crank 40 to tip the wipers lengthwise of the shoe to conform to the lengthwise slope of the bottom of the forepart. In the holder 36 is a sleeve 42 which carries the toe wiper head 44 and is adjustable about an axis extending lengthwise of the shoe to tip the toe wipers laterally to conform to
35 the lateral slope of the bottom of the forepart. The sleeve 42 has thereon a lug 46 engaged by a yoke 48 which is movable by means of a screw 50 and a crank 52 to tip the wipers laterally. The parts herein
40 shown affording provision for the above-mentioned and other movements of the wipers are substantially as in prior machines.

The slide 32 is provided, at the rear, with
50 lugs 54 having interior bearings and openings below the bearings to co-operate with mechanism for determining the path or direction of the upwiping movement of the wipers. There are mounted within the lugs
55 54 a pair of sleeve members 56 having therein rectangular slots to embrace a guide comprising a normally stationary rectangular shaft 58, the members 56 being secured together by tie rods 60 and having fastened
60 between them by the same tie rods a block 62 which extends downwardly below the members 56 and has a slot which serves as an extension of the slots in said members. The rectangular shaft 58 is mounted at its
65 ends for turning movement, and it will be

understood that as this shaft is turned, the members 56 and 62 are turned with it. If the shaft 58 is so positioned that its opposite side faces are vertical, or parallel to the direction of movement of the main wiper 70 support 20, no movement laterally of the shoe will be imparted to the slide 32 as the wipers are moved upwardly, and the path of the upwiping movement of the wipers will therefore be vertical, as may sometimes
75 be desired in operating upon shoes made on so-called straight lasts. On the other hand, if the shaft 58 is turned so that its sides are inclined to the vertical in one direction or the other, its guiding action on the members 80 56 and 62 will result in a movement of the slide 32 laterally of the shoe, so that the wipers in their upwiping movement will actually follow a path which is correspondingly inclined.

For purposes of this invention the guiding shaft 58 is arranged to be adjusted to determine the path or direction of the upwiping movement of the wipers by the same means whereby the wipers are adjustably tipped laterally of the shoe to position them in proper relation to the lateral slope of the bottom of the forepart of the last. By reference to Fig. 2 it will be seen that the wiper-adjusting screw 50 has fast thereon a pinion 64 in mesh with a pinion 66 on a shaft 68. The shaft 68 is connected by a universal joint 70 to a telescopic shaft 72 the two parts of which are connected together by a spline 74, and the shaft 72 is connected by a universal joint 76 to a worm-shaft 78 mounted in bearings at the base of the machine. The worm on the shaft 78 engages and operates a toothed sector 80 connected by a crank arm 82 and a link 84 to a crank arm 86 on the rectangular shaft 58. These connections are so arranged that when the wipers 18 are horizontal, as far as tipping movement laterally of the shoe is concerned, the opposite sides of the shaft 58 are vertical, so that upwiping movement of the wipers will be in a vertical direction. On the other hand, any lateral tipping movement of the wipers in either direction, to bring them into a position in which they extend laterally in a direction substantially parallel to the lateral slope of the bottom of the forepart of a right or a left last, is accompanied by a turning movement, in equal degree and in the appropriate direction, of the shaft 110 58. In all positions of adjustment of the wipers, whether for right or left shoes, for different styles of shoes, or simply for variations in the positions of different shoes, there is thus insured a uniform angular relation (as herein shown a right angular relation) between the direction of the upwiping movement of the wipers and the direction in which the wipers extend laterally of the shoe, and there will accordingly be a 115 120 125 130

substantially uniform angular relation, in operating upon different shoes, between the direction of the upwipe and the lateral slope of the bottom of the forepart of the last.

5 The direction of the upwipe is thus determined directly by reference to conditions at the forepart of the shoe, where the wipers are to operate, and without requiring of the operator of the lasting machine any adjustment other than he has been accustomed to make heretofore.

Having described the invention, what I claim as new and desire to secure by Letters Patent of the United States is:—

15 1. In a machine of the class described, the combination with last and shoe positioning means, toe-embracing wipers, and means for imparting to said wipers upwiping movement in a variably predetermined direction heightwise of the toe of the shoe, of mechanism for determining the direction of the upwiping movement of the wipers by the lateral slope of the bottom of the forepart of the last.

25 2. In a machine of the class described, the combination with last and shoe positioning means, toe-embracing wipers mounted for tipping movement to conform to the lateral slope of the bottom of the forepart of the last, and means for imparting to said wipers upwiping movement heightwise of the toe of the last, of mechanism adjustable to vary the direction of the upwiping movement of the wipers, and means connected to the

35 wipers for adjusting said mechanism in accordance with the position of the wipers.

3. In a machine of the class described, the combination with last and shoe positioning means, of toe-embracing wipers movable heightwise of the toe of the shoe to upwipe the upper and adjustable about an axis extending lengthwise of the shoe to position them in proper relation to the bottom of the forepart of the last, and a single means for thus adjusting said wipers and for simultaneously varying the direction of their upwiping movement.

4. In a machine of the class described, the combination with last and shoe positioning means, toe-embracing wipers, and means for imparting to said wipers upwiping movement heightwise of the toe of the shoe, of means for adjusting said wipers about an axis extending lengthwise of the shoe, a device adjustable to determine the direction of the upwiping movement of the wipers, and connections between said device and the wiper-adjusting means for adjusting said device simultaneously with the wipers.

5. In a machine of the class described, the combination with last and shoe positioning means, toe-embracing wipers, and means for imparting to said wipers upwiping move-

ment heightwise of the toe of the shoe, of means for adjustably tipping said wipers to incline them laterally of the shoe in proper relation to the bottom of the forepart of the last, and controlling mechanism adjustable with the wipers and arranged to direct their upwiping movement in a path bearing the same angular relation to the lateral inclination of the wipers in all positions of their adjustment.

6. In a machine of the class described, the combination with last and shoe positioning means, of toe-embracing wipers movable heightwise of the toe of the shoe to upwipe the upper and adjustable about an axis extending lengthwise of the shoe to position them in proper relation to the bottom of the forepart of the last, and means for insuring a uniform angular relation in all positions of adjustment of the wipers between the direction of their upwiping movement and the direction in which they extend laterally of the shoe.

7. In a machine of the class described, the combination with last and shoe positioning means, of toe-embracing wipers adjustably mounted for tipping movement laterally of the shoe and also movable heightwise of the toe to upwipe the upper, and means for insuring that in all positions of the wipers their upwiping movement will be in a direction substantially perpendicular to the direction in which they extend laterally of the shoe.

8. In a machine of the class described, the combination with last and shoe positioning means, of toe-embracing wipers movable heightwise of the toe of the shoe to upwipe the upper and mounted also for tipping movement to position them in proper relation to the bottom of the forepart of the last, and means controlled by the tipping of the wipers for determining the direction of their upwiping movement.

9. In a machine of the class described, the combination with last and shoe positioning means, of toe-embracing wipers, means for adjustably tipping said wipers laterally of the shoe, a wiper support movable heightwise of the shoe to cause the wipers to upwipe the upper and relatively to which the wipers are bodily movable laterally of the shoe, a guide operative in response to movement of said support to move the wipers laterally of the shoe, said guide being adjustable to determine the direction and the extent of such lateral movement of the wipers, and connections between said guide and the wiper-adjusting means for adjusting the guide with the wipers.

In testimony whereof I have signed my name to this specification.

ARTHUR F. PYM.
